UNITED STATES PATENT OFFICE.

JOHN MCBREARTY, OF ROSEMONT, PENNSYLVANIA.

SHOE.

1,372,709.

Specification of Letters Patent. Patented Mar. 29, 1921.

Application filed March 15, 1918. Serial No. 222,532.

To all whom it may concern:

Be it known that I, JOHN MCBREARTY, a citizen of the United States, and a resident of Rosemont, county of Montgomery, State 5 of Pennsylvania, have invented certain new and useful Improvements in Shoes, of which the following is a specification.

My invention relates to an improvement in shoes wherein an inner shock absorbing portion is inserted against the foot or very close thereto, so that the foot may have the benefit of all of the resiliency of the cushioning means instead of interposing between the foot and the artificial cushion a substantially solid layer of leather and nails, or the equivalent. In addition to supplying the suitable parts which are to be used adjacent to said cushion, I have inserted an arch supporter of new and improved form which 10 operates with the flexible pad and with the flexible pad supporter or container, later to be referred to, and whereby the arch supporter by influence thereon of the shell or container serves to maintain the arch of the 15 foot in proper conformation by maintaining the shoe beneath and to one side of the instep of the foot with suitable convexity. In performing this function, the arch supporter is not bodily displaced laterally or 20 longitudinally, nor is it flattened by pressure thereon, but it may be distended at the forward end as a result of pressure applied thereto without displacing the parts of the 25 shoe in the vicinity thereof. In addition to 30 a cover for the pad above referred to, I have supplied a metallic heel cup which is of such longitudinal extent as to coöperate with the above mentioned arch supporter and of such depth as to contain the flexible pad or 35 support and also repel all nails and the like 40 from passing into and through said shock resisting material.

Reference to Patent No. 1,148,604, dated August 3, 1915, issued to myself, shows 45 many similarities between the shoe manufactured under that patent and a shoe constructed in accordance with my present invention. However, the differences which I have introduced into the construction later 50 to be described, are such as to introduce very radical improvements in shoes manufactured in accordance with said patent.

One important and very essential improvement which I have effected in my 55 latest form of shoe construction resides in the fact that said form can be repaired, as

desired, and repeatedly, and the inner surface of the shoe at the heel is always maintained as smooth as the surface of the new shoe. This feature is most important because repaired shoes are becoming more important commodities during the present period when the price of shoes has been tremendously increased. To some who have heretofore worn repaired shoes the absence 60 of the roughened surface of the heel and of the nails themselves after a little wear, which are necessary incidents in connection with the attachment of the heel to the repaired shoe, is a boon and a distinct advantage. To those who never have worn repaired shoes heretofore on account of tender feet and many other reasons but who are now, or presently will be, obliged to resort to repaired shoes, the smooth heel of 70 my improved shoe after repair will appeal 75 as a material advance in the manufacture of shoes.

It will be at once recognized that shoes fitted with rubber heels also become rough and uncomfortable at the inside of the heel after repeated renewals of the rubber heel owing to the necessity of driving the fastening means and clenching the nails in the vicinity of the heel of the shoe, but complete relief from this fault is obtained in my improved form of shoe which also contains the provision for the absorption of shocks possessed by the rubber heel.

In the shoe later to be described, the nails 80 driven through the heel to attach it to the repaired shoe can never reach the cushion member as they are repelled by the pad container and clenched at a distance from the space occupied by the heel of the wearer. 85

In addition to overcoming the above mentioned circumstances, I find it possible in the improved form of shoe construction hereinafter to be described, to use an ordinary last which, furthermore, need not be 90 fitted with a steel plate either fixedly, or removably. As a result of the construction embodied in a shoe which shall later be described, I have effected an improvement in a shoe having an inner cushion for the foot 100 which can be repeatedly repaired without injury to the shock absorbing pad, and there is also present in this construction a shoe in which the nails fastening the heel thereonto cannot project into the immediate 105 vicinity of the foot of the wearer.

There is still another advantage in that

the shoe which I have produced may be made upon a simple wooden last, without adding thereto steel plates to form a protection against nails or other fastening means at the heel thereof, which are continuously present to repel the points of the nails used to fasten the heel to the inner sole.

An improved heel construction, effecting 10 a saving in leather, also results from the form of shoe proposed by me, in that I shape the rear of the shoe so as to bring the level of the foot to the same level of the foot in the ordinary shoe, and, therefore, in making 15 room for the thickness of the pad, I remove a portion of the heel and thus make its volume less. I construct the heel which I shall use upon the shoe contemplated by me out of smaller pieces of leather than are 20 ordinarily employed in the best quality of heels. In this way a considerable saving in sole leather or equivalent materials in the manufacture of heels is effected. Nevertheless, I can replace the wear resisting 25 outer layers of my heel at will and thus am not obliged to sacrifice the qualities of the present style of heel in order to effect the saving in material referred to.

By the coöperative use of the shell container and the particular form of arch supporter together with the action of the interposed inner sole, I have introduced a desirable form of arch supporter which is firmly positioned and maintained in place 35 so as to perform the function assigned to it in an advantageous manner.

In the drawing accompanying this specification and relating thereto, Figure 1 shows a well known last without a metallic shield 40 at heel, and placed thereon some of the members which I have introduced into the construction of shoes; Fig. 2 is a fragmentary view and shows the same parts in place and added thereto an upper with lining, an 45 inner sole and welt, and my improved arch supporter; Fig. 3 shows another advance in the manufacture of the improved shoe and presents the shoe of my invention in a fragmentary view with the outer sole fastened 50 to the other parts and with a heel fastened in place; Fig. 4 shows a vertical longitudinal section of a shoe manufactured in accordance with my invention and has a foot depicted therein so as to show the combined arch supporter function of the pad and arch supporter plate; Fig. 5 is a section on line 5—5 of Fig. 4, showing the heel attached to the outer and inner sole, the shell, pad and cover, and the upper, lining 55 and counter all in section; Fig. 6 shows, in perspective, the form of arch supporter used by me; Fig. 7 shows, in perspective, the shell, the inner sole and the arch supporter as a unit and in coöperative relation; and 60 Fig. 8 shows a detailed section through the

forward part of the shell which includes a section of the inner sole and arch supporter, adjacent parts being omitted.

The shoe made in accordance with my invention is best described by a showing and a description of the action of assembling and fastening together the various parts of a shoe rather than to describe the parts in place in a view like Fig. 4. For instance, a last 1, of selected size for the shoe intended to 75 be made, is used upon which to unite the various shoe parts, the upper 10, welt 11 and lining 12 of the shoe are omitted for the sake of clearness, but they appear in Fig. 2 in place and connected to the inner sole 5. 80 Upon the heel of said last 1 is placed the cushion cover 2 and upon and above the cover is located the cushion or shock absorbing member 3. While I intend to utilize a cover 2 or the equivalent for the purpose of 85 interposing a layer of wear resisting material between the foot of the wearer and the pad 3, which also holds the pad firmly in place, I also contemplate the construction and assemblage of parts wherein the pad 90 has no cover such as shown by 2 in the drawings but may have an outer layer incorporated therein which shall serve as a smooth surfacing wear resisting member. Under such conditions the pad 3 and shell 4 95 will be united by cement or in some equivalent manner and means will be provided for holding the pad in place other than where it will be fastened to said shell 4. With this arrangement I may also use a pad which 100 shall not need an upper surface layer because the material of which it is composed is homogeneous throughout and is also suitable for contact with the foot of the wearer inclosed in a stocking. I have experimented 105 with a number of materials for use in this pad and have found many satisfactory. I contemplate the use of such material as shall retain its resiliency and continuity and be long wearing. Necessarily, the upper surface of the cushion 3 is smooth and substantially flat, so that the foot of the wearer shall not be inconvenienced by any distortion of the surface thereof, whereas, the under portion of the cushion or pad, now uppermost, has a considerable convexity in order 110 to provide a sufficient depth to said pad and thus permit the insertion beneath the heel of the wearer of a sufficient thickness of flexible material to take up all shocks. The cushion 115 3, at its edges, is tapered off to a thin edge, so as to fit the sides of the shoe and not form an uncomfortable edge for the foot of the wearer. The cushion containing shell 4, in this case made of steel, although I expect 120 to use other materials, is then placed over the heel end of the pad 3 and being of dished form, its inner surface is substantially in contact with the pad throughout the entire concave surface of said shell. The concave 130

portion of the shell may be left unfinished and with a rough surface, but the convex surface is preferably polished in order to more easily turn and clench nails and like fastening means. Cement or other means may be used to more intimately unite the shell and pad. The next step is to lay an inner sole 5 upon the shell 4 and to fasten the same at the waist and ball of the last by tacking or by any other suitable means. The next step is to fold the cushion cover 2 over the margin of the inner sole 5 at the rear-most portion thereof so that the inner sole 5 is interposed between the shell 4 and the turned over portion of the cover 2. When this is done the upper 10 is then pulled over at front and rear and the usual lasting operations are carried out in which the upper and welt 11 are brought into proper position relative to the inner sole and are tacked in place on the last 1 around the edge thereof. At the heel, the upper and the cushion cover are neatly pulled over onto the last and tacks are driven to hold them, and tacks are placed near the edge of shell 4 and clenched over onto the shell to hold it in place on the last, then the cushion, cover, shell and upper are correctly positioned and held in place over the inner sole.

As the inner sole 5 is suitably channeled near its edge, and as the welt 11 is sewed to the inner sole by sewing through the flap produced by channeling when the sewing of the inner sole and welt has been carried out and completed and the parts are properly united, the tacks fastening the inner sole and other parts are removed.

When the parts are united as just described, my improved form of arch supporter is positioned upon the upper surface of the inner sole and by reason of the driving of the tangs 8 and 18 thereon into the inner sole the arch supporter 6 is semi-fixedly positioned. The tangs 8 are dimensioned so as to solidly embed themselves in the material of the inner sole but are not long enough to pass altogether therethrough and into permanent contact with the shell 4. The tangs 18 are of somewhat shorter length than the tangs 8, and they are made shorter so that when the arch supporter 6 is in intimate contact with the inner sole 5 the tangs will not pass through the inner sole 5 but will simply embed themselves therein and be firmly held thereby. A tang 19 is shown on the arch supporter 6 and it is given practically the same dimensions as the tangs 18; it is turned in a direction opposite to the tangs 18. The purpose of the tang 19 is similar to that of tangs 18 for it is intended to be forced into the material of the outer sole in a manner later to be described. Referring additionally to the tangs 18 and 19 it should be noted that while I have shown three in all, I contemplate the use of a

greater number and even of a less number as the case may be and I also intend to position them and form them in various and different ways.

In placing the arch supporter 6 care is taken to locate it so that it shall have a definite position with regard to the shell 4 with which it coöperates and reference should therefore be made to Figs. 7 and 8 for a clear understanding of the relation of the arch supporter 6 and the shell 4.

Bearing in mind that a left shoe is depicted in the drawings, it will be seen that the arch supporter 6 is carried as far as possible to the inner edge of the inner sole and the shell 4 and thereby is elevated at its inner edge 20 by reason of the fact that it fits about and on the curvature of the end of the shell 4. In this position the inner edge 20 serves to force the inner sole 5 above it and the cushion 3 into a position where they are both sloped from the inner edge of the shoe outwardly.

The slope imparted to the inner sole and the cushion is made to closely approach that of the arch of the foot and thereby to maintain the parts of the shoe in contact with the sloping portion of the under part of the arch of the foot. Under these conditions when the weight is thrown on to the foot and the os calcis depresses the pad at the rear of the arch of the foot as later described, the sloped shank of the shoe acts very effectively as an arch supporter.

Furthermore, it should be noted that on account of the sloped surface of the shank of the shoe and also on account of the fact that the arch supporter 6 is located as far as possible to the inside of the shoe the bones of the foot do not bear upon the bent metal support 6 and straighten it out into merely a flat piece of metal. The arched shape of the support is also maintained due to the fact that the tangs 18 and 19 are solidly inserted into the inner and outer soles and hence cannot move away from their original position therein. The tangs also prevent any transverse displacement, consequently the bone of the foot at the outside edge of the foot, the metatarsus, is prevented from taking a position over the arch supporter 6 and bend it into a flat condition.

It should be understood that I control the position of the arch supporter so as to prevent the edge 20 thereof from taking a position forming a continuous edge with the edge of the shell 4. It is necessary to leave a margin 21 between the edge of the shell 4 and the edge 20 of the arch supporter for the purpose of accommodating the seam which is necessarily found at this place.

I have, therefore, formed an efficient unitary device comprising the shell 4, the inner sole 5 and the arch supporter 6 which unit is clearly shown in Fig. 7. At the broad end of the arch supporter and between

the tangs 8 I have formed an arcuate or cut out portion permitting of a close connection between the parts as well as permitting the central thickened portion of the shell 4 to become depressed without interfering or contacting with the end of the arch support as would otherwise occur if the ends were squared across for in that case the flat surface under the shell 4 would with repeated impacts, due to walking, destroy the convexity of the shell 4. As formed with the cut out portion the arch supporter 6 is placed in close contact with the shell, and as contact is made only on the points and the tangs there is no tendency to displace adjacent parts.

I have also effected a suitable relation between the shell and the arch supporter by off-setting the arch supporter just forward of the arcuate or cutout portion referred to to form the portion 22. This part 22 of the arch supporter is placed just over the shell 4 and adjacent to the edge thereof, and forms a bearing surface tending to aline the arch supporter with the general direction of the shell 4. In order to adjust this alinement the ends 7 may be raised or depressed as desired.

In view of the foregoing description it is evident that the unit shown in Fig. 7 represents a new and important construction in shoes for through the agency of the inner sole and the outer sole which hold the arch supporter 6 in place, the shell 4 acts as a foundation member upon which to position and hold in place the arch supporter 6 which is thereby given a slant to form the sole of the shoe to the shape of the arch of the foot. It is manifest that without the shell 4 there would be no chance of fixedly holding the arch supporter 6 in the slanted position and it should be noted that the inner sole interposed between the shell and the support cooperates with both to form a rigid but flexible arch supporter.

The arch supporter 6 is shown with a particular form and is shown arched but there are no special limitations on these details. One side, namely 20, is made straight so as to permit the arch supporter to be moved to one side of the shoe, namely that side toward the other foot, and is hollowed out on the outer side to permit the metatarsus to pass thereby and not press thereupon.

The outer sole is then applied to the parts of the shoe on the last and after fitting it into proper contact with the inner sole the tang 19 on the arch supporter 6 is driven into place and the outer sole is temporarily fastened to the inner sole over the arch supporter by tacking and later sewed to the welt in the regular way. The finishing processes consisting of sanding, blackening and the like need only the slightest reference thereto. The foregoing functions of attach-

ing the upper and lining to the inner sole and later to the outer sole are well known and they are not materially different or modified in connection with the making of a shoe embodied in my invention.

Possibly reference should be made to the particular construction at the heel 9 of the shoe where the upper 10, the lining 12, inner sole 5, counter 14, and the quarter 15 are fastened together by tacks or other suitable means and at the same time the cushion cover 2 is fastened firmly in place. In addition to the fastening of these parts, the outer sole 13 is brought over and fastened through the portions above mentioned, said fastening means being headed over by the nail resisting container and clencher 4.

After the outer sole has been fastened to the other parts, nails 16 or other fastening means are driven through the heel 9 and through both the outer and inner soles and are clenched at their points against the nail resisting container 4. It should be noted that the heel 9 used by me in connection with the shoe above described comprises a relatively lesser quantity of heel material than is present in the shoes as customarily made. This is due to the fact that below the substantially flat surface of the foot there is interposed the shock resisting pad 3 which should be of substantial thickness and which is held in the convex shell 4 above referred to. The depth of all of these parts necessarily displaces the position of the inner and outer soles 5 and 13 downwardly and consequently leaves a lessened space to be occupied by the heel 4 proper. This is particularly so at the forward portion of the heel. Additionally in forming the heel described, I have introduced a new feature into the construction of shoes, namely that of arranging a space for a pad or like member and protecting said space and the shock resisting member introduced therein from nails and other means used in fastening the parts of shoes together. For instance, I believe it is entirely new in the making of shoes to employ an unshod unmetalled wooden last such as 1 and to form adjacent thereto a space into which a pad member 3 shall be inserted which shall be either covered or uncovered and then proceed to complete the shoe and fasten the parts thereof on said unprotected last and have a shoe which may be repaired without deterioration of the pad.

It is further new in the manufacture of shoes to provide a space in said shoes for a pad by the use of a nail clenching member used in conjunction with an ordinary last and this I contemplate as well as what has been already described in detail and I may say that I have in mind broadly the feature of providing in a shoe a recess into which may be entered a shock resisting member and that I include in my invention

all ways of forming such a shoe upon any last of ordinary form either shod or unshod. And in this connection I will elaborate upon what has just been referred to as an improvement upon my Patent No. 1,148,604. In that patent it is clear that a special last and parts connected thereto are necessary in order to form a shoe having such a recess or space for the insertion of a shock absorbing member.

Referring to Fig. 4 and bearing in mind the anatomy of the human foot, it will be noted that the thickest portion of the pad 3 is almost exactly in line with the os calcis 15 which is the lower prominent extension of the bone at the heel. When the weight of the body is thrown upon the foot there is considerable weight borne by the os calcis within a limited area at the heel with the result that the cushion or pad 3 beneath the os calcis is compressed more than it is under the arch 17. Consequently due to the new difference in level between that of the heel and that of the arch the pad serves to act 20 automatically as an arch supporter as well as a shock absorbing member. It should also be noted that this action of the pad in serving as an arch supporter becomes more and more important as the load upon the os calcis increases and the pad always adjusts its action as an arch supporter to the 25 variations in load upon the level.

In the foregoing and in the drawing, the longitudinal extent of the pad or cushion 35 has not been referred to, although in the drawing it is terminated at substantially the waist of the shoe. There is no particular reason for stopping at this place and it may even be useful if made of shorter extent than 40 that shown in the drawings. On the other hand, my invention is equally applicable to a shoe construction in which the pad extends entirely along the sole, as in the case of my Patent No. 1,148,604.

45 In the foregoing I have, for the sake of directness and clearness of description, referred to the specific parts and a particular manner of connecting said parts and I therefore wish to state that I contemplate all of 50 the various means of accomplishing the result which has been described and shown in a particular way in the foregoing. Under no circumstances do I intend to limit my invention to only that which has been described by me.

Having thus described my invention, what I claim and desire to protect by Letters Patent is:

60 1. A shoe having in combination, an inner sole and outer sole, a heel, an upper, a counter, a lining, and a quarter, a flexible shock absorbing pad, a cover and a nail resisting container therefor, said cover being drawn over the end of said container

and fastened to the adjacent portions of the 65 shoe, and said heel being attached to the adjacent parts by attaching means, which are prevented by said container from extending to and through said pad.

2. A shoe having in combination, an inner and outer sole, a shock absorbing pad therein, a nail resisting container therefor, an arch supporter suitably shaped and having an arcuate end comprising several tangs whereby said supporter may be fastened on 75 an adjacent part, said arcuate construction serving to permit the fastening of the supporter well back on the shoe without introducing an excess of rigidity due to the presence of said supporter under said container. 80

3. A shoe having in combination of inner and outer soles, a cover therefor, a short heel pad at the heel portion of said inner sole, and a metal piece interposed between the inner sole and said pad whereby the 85 latter is protected from nails fastening said soles together, said cover provided with a turnover portion so arranged that the margin of the heel portion of the inner sole is interposed between said turnover portion 90 and said metal piece for fastening said turnover portion to said inner sole.

4. A shoe having in combination of an inner sole, a metallic shell fitting against the heel portion of said inner sole, a resilient 95 pad lying on said shell, a cover fitting over the upper surface of said pad, and having its side and heel margins drawn over the edges of and under said pad, shell and inner sole, and means for securing said margins to 100 said inner sole.

5. A shoe having in combination of an inner sole having a concave inside heel portion, a metallic shell having a convex under surface fitting into said concave heel portion, and a concave upper surface, a resilient 105 pad tapering toward its side edges, fitting into and covering the concave portion of said shell, and a cover of flexible material fitting over the upper surface of said pad 110 and having its side and heel margins drawn over the edges of and under said inner sole, and secured to said inner sole.

6. A shoe having in combination of an inner sole, an outer sole, a metallic shell 115 fitting against the heel portion of said inner sole, a resilient pad lying on said shell, a cover fitting over the upper surface of said pad and having its side and heel margins drawn over the edges of and under said 120 inner sole, and means to fasten together said inner and outer soles with said margins secured between said soles.

In witness whereof I have hereunto set my hand this 12th day of March, A. D. 125 1918.

JOHN McBREARTY.
